UNITED STATES PATENT OFFICE

EDWARD S. WOOD, OF CINNAMINSON, WILLIAM E. HADEN, OF HADDONFIELD, HARRY C. SHARP, OF CAMDEN, AND LEON H. ASHMORE, OF COLLINGSWOOD, NEW JERSEY, AS-SIGNORS TO THE ESTERBROOK STEEL PEN MANUFACTURING CO., OF CAMDEN, NEW JERSEY, A CORPORATION OF NEW JERSEY

PEN

Application filed December 23, 1926. Serial No. 156,566.

Our invention relates to that type of writing pens particularly adapted for the production of relatively broad lines of uniform width; such pens being employed by sign writers, engravers, and the like, and the 5 principal object of our invention is to provide an improved reservoir attachment for pens of this character.

One object of our invention is to provide 10 an adjustable element carried by the pen and spaced from the nibs of the same to provide a reservoir in which a body of ink will be held by capillary attraction and fed to said nibs as required.

15 A further object of our invention is to construct the element forming such reservoir from non-ferrous sheet metal susceptible of ready flexure whereby its position with respect to the nibs of the pen may be changed 20 at will in order to insure proper feed of inks of various consistencies.

25 A further object of our invention is to provide the reservoir forming element with a rounded tip at the extremity of the same from which the ink normally sustained or retained by said element with respect to the pen may flow to the nibs of the latter as said nibs are flexed or spread during use.

30 A further object of our invention is to provide the reservoir forming element with a rounded tip at the extremity of the same with an upturned rim or lip; such rounded end presenting a substantially cup-shaped contour or form.

35 And a still further object of our invention is to provide such reservoir forming element with an elongated opening extending substantially to such rounded tip.

40 These and other features of our invention are more fully described hereinafter; reference being had to the accompanying drawings, in which:

Figure 1 is a front elevation of a pen 45 equipped with the reservoir-forming attachment constituting our invention.

Fig. 2 is a longitudinal sectional view of the pen and the reservoir attachment.

50 Fig. 3 is a side elevation looking in the direction of the arrow, Fig. 1.

Fig. 4 is an enlarged sectional view of the pen and its reservoir attachment in position of use; illustrating also the body of ink held by capillary attraction between such reservoir attachment and the pen.

Figs. 5 and 6 are cross sectional views on the lines V—V and VI—VI, Fig. 4, respectively.

Fig. 7 is a front elevation of a portion of a pen and the reservoir forming element; showing a modification of the rounded tip particularly applicable to pens in which the writing end or spoon is split into more than two points or nibs.

Fig. 8 is a sectional view on the line 65 VIII—VIII, Fig. 7, and

Fig. 9 is a view similar to Fig. 7, showing the application of a reservoir forming element having a cup-shaped tip to a pen having a writing spoon of a different shape.

The pen proper may be of the type illustrated in the prior patent of Edward S. Wood, No. 1,305,046, dated May 27, 1919; comprising a substantially semi-cylindrical body 1, with the usual shank 2, for engagement with any suitable form of holder, and having the usual eye 3, forming the upper termination of a slit 4, which bifurcates the point to form the separate nibs 5 and 6, which are extended obliquely outward and are complementary to form the ink dispensing spoon consisting of the upturned ends 5^a and 6^a, of such dimensions as may be desired.

It is desirable in the use of pens of this character that a reservoir device be employed therewith, in order that a steady and constant flow or supply of ink for considerable work may be maintained adjacent the writing spoon or other portion of the pen contacting with the material written upon. In 90 the present instance we have provided a reservoir forming element that is adjustable with respect to the pen, and one that has a rounded tip from which the ink will feed from the supply directly to the writing portion or nibs of the pen; one form being shown in Fig. 1, of the drawings.

When employed with pens having more than one slit; thereby providing more than one nib, it is desirable to insure that the flex-

ing of the nibs will not cause them to engage or catch upon the rounded end of the reservoir forming element, and for this purpose such rounded end is preferably made cup-shaped, as indicated in Figs 7, 8 and 9; the ink flowing to the writing portion of the pen from the rounded under surface of such cup-shaped end.

In the pen illustrated in the accompanying drawings, the up-turned end portions are substantially semicircular in contour, capable of producing a line having circular terminals, although it will be understood that such end portions may be of different shape without departing from our invention. As in the patent referred to, the so-called spoon formed by the upturned nib ends 5^a and 6^a, is disposed in oblique relation to the axis of the body of the pen so as to be parallel to and in flat engagement with the surface to be scribed when said axis is disposed at an angle approximately 45° to the plane of such surface.

Carried by the pen is a flat finger 10, overlying the same in the position clearly illustrated in the drawings, and this finger may be provided with spring clips or wings 11, adapted to embrace the pen body adjacent to the shank 2, whereby said finger may be held in inclined relation to the outer surface of the pen body and across the eye 3 of the same. This finger is provided with an elongated aperture 12, somewhat wider at the rear portion than at the forward portion, which aperture extends into and relatively close to the gradually tapered part 10^a of said finger 10; said tapered part being disposed within the side margins of the pen so as to be out of the way when the pen is used for ruling purposes by contact with a straight-edge, and this narrowed portion of the finger terminates in a substantially circular end 13, overlying the nibs 5 and 6, just short of the upturned ends 5^a and 6^a of the same.

The common practice heretofore in the use of reservoir-forming elements of this type, and as indicated in the prior patent before referred to, is to have the narrow terminal of the finger in actual contact with the nibs of the pen. It has been found, however, that inks vary greatly in consistency and fluidity, and it is frequently objectionable to have this contact since in the thicker inks it tends to slow up the flow and in some instances, cut it off entirely when the engaging portions 5^a and 6^a of the nibs are in actual contact with the card, paper or other object upon which the line is scribed. An important object of our invention, therefore, is to provide this reservoir-forming finger in spaced relation with respect to the pen so as to prevent this slowing up or cutting off of the flow.

Additionally, the finger is preferably made of nonferrous metal that may be more or

less readily flexed; German silver being preferred, and the user is able to increase or decrease the amount of separation between said finger and the nibs of the pen and insure ready flow to the spoon constituted by the upturned portion of the nibs 5^a and 6^a. The flow of ink from the reservoir is also facilitated by the presence of the extended aperture or slot 12 in said finger, and by the narrowing of such finger and its termination in the rounded end 13.

While we have described and shown a pen having a rounded writing spoon or table formed by the up-turned ends 5^a and 6^a of the nibs 5 and 6, it will be understood that such table or spoon may be square, rectangular or other shape suitable for the purpose described, and in some instances may be omitted altogether.

In Figs. 7, 8 and 9, we have shown a reservoir-forming element particularly applicable to pens having more than one slit; Fig. 9, showing also a pen having a rectangular writing end. To avoid danger of the side nibs catching on the rounded end of the reservoir-forming element, the edge or rim of the latter may be turned up slightly to cup-shape, as indicated at 13^a; these views being enlarged to show clearly this feature of our invention. In some instances, only the sides of the rounded ends may be turned up.

We claim:

1. The combination with a pen having the free ends of its nibs extended at an angle to the axis of the body to form a writing table, of a flat reservoir-forming finger made of freely flexible non-ferrous metal permanently secured to the upper side of the pen body and spaced therefrom; the distance between the pen body and said reservoir-forming finger being greatest at a point remote from said writing table and gradually approaching the latter and said finger being tapered in substantial conformity with and overlying the nibs of the pen and laterally spaced from the marginal edges of the same and forming a narrow neck, with a circular end joined to said neck and disposed adjacent to the angularly disposed nib extensions forming the writing table and out of contact with said pen.

2. The combination with a pen slotted to form a plurality of tapering nibs terminating in end portions extended at an angle to the axis of the body to form a writing table of greater width than said nibs, of a flat reservoir-forming finger made of non-ferrous flexible metal permanently secured to said pen and free for adjustment from and toward the nibs of the same; said finger having a tapering neck portion laterally spaced from the marginal edges of the pen nibs with an elongated tapering aperture overlying the slit between the nibs and extending close to its end which terminates in a circular por-

tion joined to said tapering neck; the opposite sides of said circular portion extending to the marginal edges of the pen nibs just short of the angular extensions thereof.

5 In witness whereof we have signed this specification.

EDWARD S. WOOD.
WILLIAM E. HADEN.
